UNITED STATES PATENT OFFICE.

EDMUND F. HARTSHORN, OF NEWARK, NEW JERSEY, ASSIGNOR TO THE STEWART HARTSHORN COMPANY, OF NEW JERSEY.

SHADE-ROLLER.

SPECIFICATION forming part of Letters Patent No. 613,800, dated November 8, 1898.

Application filed August 11, 1897. Serial No. 647,815. (No model.)

To all whom it may concern:

Be it known that I, EDMUND F. HARTSHORN, a citizen of the United States, and a resident of Newark, in the county of Essex and State of New Jersey, have invented certain new and useful Improvements in Shade-Rollers, of which the following is a specification.

My improvement relates to that class of rollers known as "extension-rollers," in which the roller is in separate sections or parts, one of which slides within the other, whereby the roller can be adjusted to fit windows of different widths. In such rollers the inner sliding section is usually constructed of wood, which slides within the metal tube or outer portion of the roller. As wood under the varying changes of the atmosphere is apt to swell or shrink, this wood portion of the roller is liable to increase or diminish in diameter, and hence either to bind in the outer tube, so that it is difficult to slide the parts on each other to adjust the length of the roller, or to become so loose that the parts move and turn in each other and the roller ceases to be firm and steady.

My improvement consists in a novel construction of this wooden extension-piece of the roller by which the variations in the wood due to swelling and shrinking are compensated and the roller maintained at a fixed diameter and all binding or loosening of the wooden section in the outer tube is prevented.

In the accompanying drawings, illustrating my improvement, Figure 1 is a view of the complete roller. Fig. 2 is a view of the wood extension-piece, showing my improvement. Fig. 3 is a section of the roller through the line *x x*, Fig. 1; and Fig. 4 is a detached view of the spring.

40 *a* is the wooden extension-piece, which slides in the outer metal tube *b*.

In constructing the roller according to my improvement I cut a slit or cleft *c* in the end of the wooden section near the edge and for about two-thirds of the length of the section, so as to form a tongue or semidetached portion *d* along the surface of the section. In this cleft *c* or the space under the tongue I insert a spring *e*, by which the tongue is pushed outward from the section and by means of which the tongue is caused to act as a spring and press against the inside of the outer metal tube when the wooden section is inserted in the same. As will be read-

ily understood, if the wooden section swells 55 so as to increase its diameter the tongue *d* is compressed or pressed inward sufficiently to restore the diameter to its normal size, and if, on the other hand, the wood shrinks and becomes smaller than the outer tube the 60 spring *e* forces the tongue *d* outward sufficiently to maintain an even pressure in the tube. The tongue *d* therefore, as is seen, compensates for all the variations in the size of the wooden section, yielding when the section 65 swells and springing outward when it shrinks, and thus maintaining a fixed diameter and insuring an even and constant pressure of the wooden section in the outer tube. It is found that one such tongue or a tongue 70 on one side of the section is sufficient to accomplish the purpose desired, the compression of the tongue on one side compensating for the swelling in all directions of the wooden section.

75 The cleft *c*, and consequently the tongue *d*, may be of any form and construction desired, but I prefer the construction shown in the drawings. As there seen, the cleft is circular and is merely a saw-cleft formed by a barrel-saw, and the spring used is a curved steel band, which fits in the curved cleft and should be of such a size as to force the outer end of the tongue *d* slightly outward and permit the end of the tongue to be pressed inward below 80 the circumference of the section.

85 What I claim is—

1. In an extension-roller, in combination, an extension-piece adapted to slide in a section of the roller; a spring-section connected 90 therewith, whereby the extension-piece is capable of expansion and compression; and a spring situated between the spring-section and the extension-piece, substantially as described.

95 2. In an extension-roller, the wooden extension-piece *a*, having the spring-tongue *d*, curved cleft *c* and curved spring *e*, whereby the extension-piece maintains a uniform and even pressure in the roller, substantially as 100 described.

Signed at Newark, in the county of Essex and State of New Jersey, this 10th day of June, A. D. 1897.

EDMUND F. HARTSHORN.
